DESIGN FOR A CHAIR

Hollis S. Wilhite, Chicago, Ill., assignor to Alva Lowrey and Hollis S. Wilhite, partners doing business as Toby Clark Company, Chicago, Ill.

Application August 16, 1939, Serial No. 86,739

Term of patent 7 years

To all whom it may concern:

Be it known that I, Hollis S. Wilhite, a citizen of the United States, residing at Chicago, in the county of Cook and State of Illinois, have invented a new, original, and ornamental Design for a Chair, of which the following is a specification, reference being had to the accompanying drawing, forming part thereof.

Fig. 1 is a view in side elevation of a chair embodying my new design;

Fig. 2 is a plan view of the chair, and

Fig. 3 is a front elevational view thereof on a reduced scale.

I claim:

The ornamental design for a chair, as shown.

HOLLIS S. WILHITE.
